UNITED STATES PATENT OFFICE.

EDWIN C. WORNS, OF NEW YORK, N. Y.

BOILER-REPAIR PLUG.

1,241,597.

Specification of Letters Patent.

Patented Oct. 2, 1917.

Application filed May 5, 1916. Serial No. 95,573.

To all whom it may concern:

Be it known that I, EDWIN C. WORNS, a citizen of the United States, and a resident of the city of New York, borough of Manhattan, in the county and State of New York, have invented a new and Improved Boiler-Repair Plug, of which the following is a full, clear, and exact description.

My invention relates to a device for closing leaks in range boilers, kitchen utensils, and other vessels and containers. Various expedients are employed for plugging a hole in articles of the class referred to, but, invariably, these become ineffective in a shorter or longer time according to the character of the repair device, so that leakage again occurs at the point of repair.

The general object of my invention is to provide a repair plug that will effectively close the leakage hole and maintain the same closed for an indefinite period.

A further object of the invention is to provide a repair plug that may be applied with facility, even to a range boiler, the interior of which is not accessible for the manipulation of the plug.

The invention will be particularly explained in the specific description following.

Reference is to be had to the accompanying drawings forming a part of this specification in which similar reference characters indicate corresponding parts in all the views.

Figure 1 is a side elevation of a range boiler partly broken away, showing the manner of applying the inner member of my improved device;

Fig. 2 is a transverse section taken through my improved plug and through the wall of the repaired article, the view showing the plug in position sealing a hole of the wall;

Fig. 3 is a front view of the improved plug;

Fig. 4 is a view similar to Fig. 3 but showing a slightly modified shape of the device.

My invention includes an inner clamp plate 10 formed on which, at the center, is a stud 11.

The said stud 11, for its major portion and except at the base and extreme outer end, is threaded, and is adapted to receive an outer clamp plate or disk 12, which has a threaded bore to take onto said stud. On the outer face of the disk 12, wings 13 are provided for turning the same, the disk thus

constituting in effect, a combined wing nut and clamp.

The opposed faces of the clamp disks 10 and 12, are adapted to receive washers 14 of asbestos or rubber, according to the character of the article to which the device is applied. It will be observed that the opposed faces of the disks, 10, 12, are concave, the idea being to give an effective gripping action at the peripheral edges of the plates and to accommodate the washers without causing the same to be forced to any appreciable extent beyond the edges of the disks and thereby maintain an ample portion of the washers within the disks to give a more effective fluid-tight binding action of the washers against the opposed surfaces of the boiler A, or the like. The faces of the plates, 10, 12, are formed with grooves 15, preferably annular and therefore continuous, the grooves serving to give an effective engagement with the washers and assisting in preventing the forcing of the washers edgewise from between the clamp plates.

The washers are perforated at the center for the passage of the stud 11. It will be noted from Fig. 2 that the base 16 of the stud 11 is conical so that when the said stud is passed through a hole α to be sealed, the base 16 will be wedged into the hole expanding the same to a uniformly round and smooth edge. The base 16 will of itself form a complete closure of the hole α and thus materially aid in stopping the leak. Any leakage, however, around the base 16 will be effectively taken care of by the washers 14 under the pressure of the clamp plates 10, 12.

It is exceptionally difficult to stop a leak in a range boiler, or the like, as the various expedients on the market have failed in practice to maintain the leak sealed for any great length of time. The base 16 is smooth and unthreaded. Devices are known that include a conical screw which cuts its own thread in the wall of the article being repaired but the wedging action of the conical screw is nullified by the screw thread which it cuts.

The clamp plates of my improved plug in the form illustrated in Fig. 3 are round; in Fig. 4 I have shown an oval plate 12^a, designed for use where the puncture, instead of being perfectly round, is more in the form of a slit. Said oval plate is provided with wings 13^a and receives the threaded stud 11^a having an eye 17^a corresponding with the stud and eye shown in Fig. 2.

The outer end of the stud 11 is formed with an eye 17, which is adapted to receive a suspension cord 18 so that the inner disk 10 may be dropped into a range boiler A 5 through a nipple or spud *b* thereof (generally termed "spud" in the trade) and held suspended on the cord below hole *a* to be repaired. A hook 19 is then employed as a fishing device, said hook being inserted 10 through the hole *a* into the boiler transversely to the direction of the suspension cord 18 until the latter is engaged, whereupon, the cord is drawn outwardly through the hole *a* as indicated in dotted lines, Fig. 15 1. The cord can now be grasped until the stud 11 of the plate 10 is drawn outwardly through the hole *a*. After the stud 11 has been grasped by the workman, the cord 18 may be removed and the inner clamp plate 20 10 with its washer 14 brought to a bearing against the wall of the boiler at the interior.

The outer washer 14 and outer clamp plate 12 are now applied to the stud 11 and the screwing up of the outer clamp plate on the 25 stud 11, will wedge the conical base 16 tightly into the hole and bind the washers firmly against the opposite surfaces of the boiler.

The inner washer 14, it will be observed, 30 snugly embraces the conical base 16 and the provision of the grooves 15 in the adjacent clamp plate, together with the concave form of the said plate to give an edge contact, insures an ample engagement of the washer 35 with the conical base so that the washer is

directly and immediately effective at the hole to be sealed. In addition, the broad surface of the washer and the edge contact of the clamp plates prevent the escape of leakage beyond the clamp plates even should slight leakage occur around the base of the stud. Finally, it is to be observed that the inner disk 10 presents a broad surface to the water pressure whereby the latter is utilized to press the inner washer against the boiler. 40 45

The bore of the outer clamp plate 12 advantageously is flared at the inner end as at 12^a so that in the event the material of the boiler A should be so thin as to cause the coned base 16 of the stud 11 to extend to the 50 washer 12, said coned base will be properly accommodated in said washer.

Having thus described my invention I claim as new, and desire to secure by Letters Patent:

A sealing plug of the class described including an inner clamp plate, a lateral stud thereon at the center, said stud having a smooth conical base, threads beyond the base, and an eye at the end of the stud beyond the threads; an outer clamp plate having a threaded bore to take onto the said stud, and provided on the outer face thereof with wings constituting the said plate a wing nut, and separate washers on the opposed faces of the said clamp plates, the said opposed faces being concave and having grooves therein for engagement with the adjacent faces of the washers. 55

EDWIN C. WORNS.
